UNITED STATES PATENT OFFICE.

HARRY J. HICK, OF ALLIANCE, OHIO, ASSIGNOR TO THE McCASKEY REGISTER COMPANY, OF ALLIANCE, OHIO, A CORPORATION OF OHIO.

DESIGN FOR A CLAMPING MEMBER FOR FILING APPLIANCES.

45,192.

Specification for Design.

Patented Feb. 3, 1914.

Application filed September 28, 1911. Serial No. 651,866. Term of patent 14 years.

To all whom it may concern:

Be it known that I, HARRY J. HICK, a citizen of the United States, residing at Alliance, in the county of Stark and State of Ohio, have invented a new, original, and ornamental Design for a Clamping Member for Filing Appliances, of which the following is a specification, reference being had to the accompanying drawing, forming part thereof.

The figure is a perspective view of a clamping member for filing appliances, showing my new design.

I claim:

The ornamental design for a clamping member for filing appliances, as shown.

HARRY J. HICK.

Witnesses:

GEO. C. RUSSELL,
F. C. URAN.
